INTERLOCKING FLEXIBLE COMPOSITION
SHINGLE

John Robert, Chicago, Ill., assignor to Globe
Roofing Products Co., Inc., Whiting, Ind., a
corporation of Indiana

Application April 29, 1950, Serial No. 159,001

4 Claims. (Cl. 108—7)

1

The present invention relates to preformed roofing, siding or other building structure covering materials and more particularly to preformed flexible shingles, although certain features thereof may be employed with equal advantage for other purposes.

It contemplates more especially the provision of improved flexible precut shingle units that are laid in courses with those of one course headlapping and sidelapping those of two adjacent shingles in the preceding course.

The flexible shingles embodying features of the present invention are generally T-shaped and comprise a head, a narrower butt or shank, and an intermediate stepped portion similar to but constituting an improvement over the general configuration illustrated in United States Letters Patent 1,849,785, issued March 15, 1932, and 2,050,218, issued August 4, 1936. In actual practice it has been found that there is a need for shingles to be offset from alignment both vertically and horizontally to cope with irregularities in the building structure. With the prior art devices, horizontal shifting to any degree is impossible without exposure of some areas and to this end, applicant has changed the number of steps between the head and shank and made them of unequal and irregular configuration rather than equal and truly rectangular configuration.

In interlocking shingles of the type with which the teachings of the present invention concerns itself, there is the T-shaped shingle configuration having oppositely disposed foot tabs at its lower edge to afford interlocking engagement with the intermediate stepped portion of the laterally offset and adjacent underlying shingle in the next preceding course. Consequently, the shingles are interlocked and held fast to each other so that high velocity winds of great force cannot loosen or remove them from their pre-arranged and anchored position. The foot tabs are also utilized to determine the position of assembly with the adjacent underlying shingles on each course relative to each other and to the preceding course, so that there is a predetermined amount of headlap of one on the other and the shingles are correctly aligned without the exercise of any appreciable care on the part of the roofer.

With the teachings of the present invention, the intermediate stepped portion is of irregular formation and has a series of intermediate steps. These intermediate steps conform in inclination with the feet locating tabs or abutments to en-

2

able a slight lateral as well as vertical offsetting of the shingles in order to conform with irregularities in the building structure or to correct accidental misalignments. As a result, the roofer need not be as precise in laying shingles embodying features of the present invention and the shingles may be rendered conformable to the building structure without exposing any part or area of the underlying shingle.

One object of the present invention is to simplify the construction and improve the effectiveness of preformed shingles.

Another object is to provide a preformed interlocking shingle which requires less material and gives greater double coverage than shingles of similar type.

Still another object is to provide a substantially T-shaped shingle of the interlocking type having a series of irregular steps disposed between the head and shank thereof to permit vertical as well as horizontal correction in alignment.

A further object is to provide an improved T-shaped interlocking shingle having a series of irregular steps in conjunction with regular steps to reduce the shingle from its wide head to its comparatively narrow shank without sacrificing coverage on superposed courses and providing the fullest double overlapping protection for a given area or unit of material.

A still further object is to provide a substantially T-shaped shingle with a series of steps of unequal size from its wide head to its comparatively narrow shank in a manner that affords slight horizontal as well as vertical displacement to insure proper alignment under all conditions without the exposure of any underlying courses.

Still a further object is to provide a substantially T-shaped shingle with feet locking tabs having an inclination corresponding with an opposite series of intermediate steps interposed between the wide head thereof and the comparatively narrow shank to afford more effective vertical as well as horizontal alignment.

Other objects and advantages will appear from the following description of an illustrated embodiment of the present invention.

In the drawing:

Figure 1 is a plan view of the shingle embodying features of the present invention.

Figure 2 is a fragmentary plan view showing an assembly of adjacent interlocking shingles like the one illustrated in figure laid in several courses as they would be on a roof of a building structure.

Figure 3 shows a development of sheet blank showing the pre-cut lines to form shingles therefrom with negligible waste.

The structure selected for illustration is not intended to serve as a limitation upon the scope or teachings of the invention, but is merely illustrative thereof. There may be considerable variations and adaptations of all or part of the teachings depending upon the dictates of commercial practice.

The present embodiment comprises a shingle 10 having a head 11 which is substantially rectangular in area configuration from which a comparatively narrow elongated shank 12 extends for communication through intermediate side shoulder portions 13. The head 11 is reduced from its width extending between vertical parallel side lines 14 and 15 through the medium of a plurality of regular and irregular steps, in this instance four steps 16-17-18-19 connected by intermediate shoulders 16'-17'-18' that are preferably though not essentially vertically or transversely disposed relative to the shingle shank base 12'.

The first regular step 16-16 defines the lower line of the head 11 while the last regular step 19-19 is adjacent to the top of the shank 12 and between the regular steps 16-19. The intermediate irregular contiguous steps 17-18 are cut on a bias so that their lower edges are obliquely inclined downwardly toward the shank base 12' to conform with the inclination of the opposite upper corners 20-21 and laterally extending upper edges 24-25 of the shingle interlocking foot tabs 22-23. The foot tabs 22-23 have outwardly and upwardly inclined top edges 24-25 which are cut on the bias to correspond in directional inclination with the lower edges of the opposite irregular intermediate steps 17-18 and the upper corner cuts 20-21.

With this construction, the shingle 10 can be shifted laterally as well as vertically or angularly adjusted for limited distances to line up the superposed courses with the building roof structure that itself may be warped, sagged, or otherwise out of line. By providing an oblique shoulder 18 conforming in angularity with the inclination or obliquely disposed upper edges 24 or 25 of the opposite locking shank tab 22 or 23, respectively, it is possible to slide a superposed shingle 10 into locking engagement with the preceding course so that the vertical median line of each shingle 10 is maintained vertically even though the underlying adjacent shingles in the preceding course are not perfectly aligned on account of roof warpage, sag, or an uneven supporting surface. This is rendered possible without exposure of the underlying surface by reason of an inclined continuous oblique line of contact between the complementary shoulder 18 and the correspondingly oblique parallel upper edge 24 or 25 on the opposite shank locking tab provides for combined horizontal and vertical adjustment which accounts for angular compensation to bring the next complementary superposed shingle 10 in line. This enables maintaining the vertical line of the T-arrangement when applied to the roof even though there is sag, warpage, or an uneven supporting surface. This can be effected without exposure of any area that would be rendered vulnerable to the elements if the irregular and correspondingly inclined intermediate steps 17-18 were eliminated and regular rectangular steps of equal size and

shape as steps 16-19 were substituted in lieu thereof. This affords more effective vertical as well as horizontal alignment of individual shingles without exposure of any underlying areas.

It should be noted that the intermediate irregular steps 17-18 measure and determine the overlap of shingle heads 11 of one course on the adjacent shingles 10 in the preceding course. The top horizontal shingle edge 26 merges with the top obliquely cut corners 20-21 which, in turn, connect with the vertical and parallel shingle head sides 14-15. The distance from the top line 26 of the shingle head 11 to the lowermost shoulder 19-19 is greater than the distance of the bottom line 27 of the shank 12 from the shoulder 19-19 by an amount that the head portion 11 of one shingle 10 overlaps the upper edge 26 of the adjacent shingle 10 therebeneath. The laterally projecting feet tabs 22-23 at each end of the shank bottom 27 which is a continuation thereof and merges therein, provide upwardly inclined interlocking engaging edges 24-25 from the points 28-29 of juncture of the tabs 22-23 with the shank 12.

It is the engaging abutment of the tabs 22-23 of one shingle 10 at the points 28-29 thereof or at any point along the inclined edges 24-25 with the corresponding inclined shoulder or shoulders 17-18 of shingles 10 to the right and left thereof in the preceding course, that the setting for a given headlap and alignment is determined. The irregular and inclined intermediate shoulders 17-18 in conjunction with the inclined edges 24-25 on the tabs 22-23 afford vertical as well as horizontal offsetting of the superposed shingle 10 relative to the adjacent shingle 10 in the preceding course without exposure of the lower shingles 10 where coverage is desired.

In the shingle assembly (Figure 2) the points 28-29 of the tabs 22-23 coincide with the points at the corners of the irregular shoulders 17-18, and the tabs 22-23 having previously been bent under the shoulders 19 of the underlying shingles 10, those portions of the tabs 22-23 above the coinciding points in the shoulders 17-18 constitute elements which interlock laterally as well as vertically for positioning and holding of one shingle 10 on another adjacent to shingles 10 in the preceding course. Not only is it possible to effect engagement in the coinciding corners, but along the correspondingly inclined edges 17-18 and 25-24 thereof to provide and compensate for irregularities in alignment.

Nails 30 in the corners of shoulders 17 serve for attachment of the shingles to the structure to be covered, and these nails 30 are located where their heads will be lapped and covered by shingles in succeeding courses.

It should be noted that in order for such shingles to be commercially practiced, they should be of such asymmetrical form for symmetrical die cutting from a sheet or web of prepared roofing material 31 with a minimum of waste (Figure 3). In cutting the web or sheet 31 is severed along the longitudinal center line 32 thereof relative to its outside edges 33-34 to form two longitudinal identical strips 35-36. The irregular and biased intermediate shoulders 17-18, in this instance two for each side, fall in the medial line of each identically slotted strip so that there is no waste except for the finishing cut along any or all longitudinal edges to provide the desired finishing edges should commercial practice so dictate along the longi-

tudinal center line 32 and/or outside edges 33-34. Without this asymmetrical design, the waste would be prohibitive and render impractical all other considerations which would otherwise be advantageous, such as the feature of providing a series of regular and irregular steps 16-17-18-19.

The first course of shingles 10 as illustrated in Figure 2, is laid in horizontal alignment with the shingle shank bases 12 on a common line and with their vertical parallel side edges 14-15 of the heads 11 in lateral abutment. The shingles 10 are then secured or anchored with nails 30, and individual shingles 10 of the next succeeding course are set over two abutting shingles 10 of the preceding course in such manner that the shanks 12 thereof with their end tabs 22-23 fall between the opposed parallel vertical edges of the shanks 12 of adjacent shingles 10 in the preceding course. The shingles 10 are preferably so dimensioned and proportioned that the spacing of such opposed shank edges of adjacent shingles in the preceding course just receives the tabs 22-23 of the superposed shingle 10. This generally determines the proper preliminary setting of the shingles 10 of one course with respect to two underlying shingles 10 of the preceding course. The superposed shingle 10 is then slid upward with its tabs 22-23 bent inwardly and passed respectively under the adjacent shoulders 19 of the laterally adjacent shingles 10. When this upward movement causes the tabs 22-23 at their corners 28-29 to strike the inclined shoulder edges 18 in the stepped intermediate portions 17-18 of such underlying shingles 10, the superposed shingle 10 will be arrested in correct position vertically with respect to the underlying shingles.

The tab corners 28-29 should then coincide with the corner of the bias cut shoulder 18. This will not always place the shingles in correct lateral or horizontal setting as the alignment may have to be corrected to compensate for irregularities in the building structure or in the laying of the preceding course or courses. Horizontal corrections in alignment are possible by reason of the inclined edges on the steps 18 which are engageable by the correspondingly inclined edges of the opposite foot tabs 22-23 to provide fully shielded engagement along the inclined edges of the steps 18. When the shingles 10 are thus set, the upper inclined edges 24-25 of the tabs 22-23 protrude upward under the shoulders 18 of the underlying shingles 10, and those portions of the tabs 22-23 above the shoulders 18 serve as hooks or abutments that interlock with the shoulders 18 of the underlying shingles 10 to hold down the shanks 12 of the shingles 10. This provides greater double coverage in overlapping courses and appreciable triple coverage, although it is generally recognized that it is more important to provide double rather than triple coverage, and with the structure embodied herein there is the greatest possible advantage procured through double coverage for any predetermined unit area of material.

It should be noted that the ornamental appearance such as the graining design illustrated in Figure 1 does not concern itself with the structural features and such may be varied within a wide range depending on the demands of commercial practice. While I have illustrated and described a preferred embodiment of this invention, it must be understood that the invention is capable of considerable variation and modification without departing from the spirit

of the invention. I, therefore, do not wish to be limited to the precise details of construction set forth, but desire to avail myself of such variations and modifications as come within the scope of the appended claims.

I claim:

1. An interlocking flexible shingle of substantially T-shape configuration comprising a rectangular head portion having its greater dimension horizontally, a rectangular shank portion of narrower width than the head portion and having its greater dimension vertically, a base at the lower end of said shank with its greater dimension horizontally, and bias shaped locking tabs having upper obliquely inclined edges, said tabs extending laterally from said shank base, said shingle being reduced in width from its widest upper head portion to its narrowest downwardly extending shank portion on opposite symmetrical side edges thereof in a series of steps involving at least one corresponding step on each side edge biased to provide an obliquely inclined lower edge parallel with the bias on the opposite locking tab of each shingle so that said bias steps interlock with complementary locking tabs of adjacent shingles to enable compensating for irregularities in the roofing structure covered therewith.

2. An interlocking flexible shingle of substantially T-shape configuration comprising a rectangular head portion having its greater dimension horizontally, a rectangular shank portion of narrower width than the head portion and having its greater dimension vertically, a base at the lower end of said shank with its greater dimension horizontally, and bias shaped locking tabs extending laterally from said shank base, said shingle being reduced in width from its widest upper head portion to its narrowest shank portion on opposite symmetrical edges thereof in a series of square and biased adjacent steps, at least one of said corresponding steps on each side edge being biased to provide an obliquely inclined edge parallel with the bias on the opposite locking tab of each shingle so that said bias steps interlock with complementary locking tabs of adjacent shingles to enable compensating for irregularities in the roofing structure covered therewith.

3. An interlocking flexible shingle of substantially T-shape configuration comprising a rectangular head portion having its greater dimension horizontally, a rectangular shank portion of narrower width than the head portion and having its greater dimension vertically, a base at the lower end of said shank with its greater dimension horizontally, and bias shaped locking tabs having upper obliquely inclined edges, said tabs extending laterally from said shank base, said shingle being reduced in width from its widest upper head portion to its narrowest downwardly extending shank portion on opposite symmetrical side edges thereof in a series of steps involving square-cut end steps and contiguous bias-cut intermediate steps on each side edge to provide an obliquely inclined lower edge parallel with the bias on the opposite locking tab of each shingle so that said bias steps interlock with complementary locking tabs of adjacent shingles to enable compensating for irregularities in the roofing structure covered therewith.

4. An interlocking flexible shingle of substantially T-shape configuration comprising a rectangular head portion having its greater dimension horizontally, a rectangular shank portion

of narrower width than the head portion and having its greater dimension vertically, a base at the lower end of said shank with its greater dimension horizontally, and bias shaped locking tabs having upper obliquely inclined edges, said tabs extending laterally from said shank base, said shingle being reduced in width from its widest upper head portion to its narrowest downwardly extending shank portion on opposite symmetrical side edges thereof in a series of steps on each side edge involving two square-cut end steps and two contiguous bias-cut intermediate steps to provide an obliquely inclined lower edge parallel with the bias on the opposite locking

tab of each shingle so that said bias steps interlock with complementary locking tabs of adjacent shingles to enable compensating for irregularities in the roofing structure covered therewith.

5 JOHN ROBERT.
